WIPERS FOR LASTING MACHINES FOR THE MANUFACTURE OF SHOES

Petrus M. R. Schoenmakers, No. 119 Gasthuisstraat, Kaatsheuvel, Netherlands

Filed Mar. 29, 1956, Ser. No. 574,700

Claims priority, application Germany Mar. 30, 1955

3 Claims. (Cl. 12—12)

The invention relates to lasting machines for manufacturing shoes, in which each two opposite wiping elements engage the edge of the shoe upper and fold over this edge by swinging in their plane over the edge of a last. Prior art lasting machines fitted with such wipers were only capable of wiping in uppers which are made on substantially straight flat bottomed lasts, because the flat wipers could not follow the shape of the last produced by the upward curvature of the last, so that the edge of the vamp had to be tacked on to the inner sole from the toe towards the waist. These tacks impair the elasticity of the shoe sole which is particularly desirable since it facilitates walking.

The invention has for its object to overcome this objection to the prior art and produces wipers for lasting machines, which wipers enable the edge of an upper to be wiped in a continuous operation from the toe of the shoe, over the ball and into the waist by simple means and without using tacks.

In solving this problem the nature of the invention consists in that the upper surfaces of a pair of wipers are provided with tongues positively movable vertically from the plane of the wipers. These tongues are rigidly or detachably clamped near the toe portion of the wipers, follow the edge contours of the inner wiper edges and terminate back of the ends of the wipers and are movable substantially vertically from the plane of the wipers.

By suitably moving pressure elements after the wipers have been closed, the tongues are moved out of the plane of the wipers and press the edge of the vamp tightly against the inner sole, following the curve of the bottom of the last to beyond the waist, so that a firm cohesion is insured by the adhesive material, e.g. glue.

Other features of the invention are set forth in the claims and are hereinafter described in detail with reference to the accompanying drawings, in which:

Fig. 1 is a section through the shoe upper with the edge of the vamp lasted up to the waist according to the invention;

Fig. 2 is a top plan view of the wipers and flexible tongues;

Fig. 3 is a cross section taken on line III—III of Fig. 2;

Fig. 4 is a cross section through the tongues on the wipers taken on line IV—IV of Fig. 2;

Fig. 5 is a fragmentary longitudinal section through a tongue made from flexible material engaged by a pressure element; and

Fig. 6 is a fragmentary longitudinal section through a tongue composed of a series of plates each engaged by a pressure element.

According to the preferred form of construction, the wipers comprise upper engaging elements 12, 13 which are urged towards the shoe last 23 by means on the element 32. The elements 12, 13 will wipe the vamp edge 24 of the shoe upper 22 over the edge of the last 23. The upper 22 is retained on the last 23 by means of

2

work holders 27, 28 and is kept taut by the upper wiping elements 12, 13 and pressure element 32. The element 32, as shown in Fig. 1, is provided with pressure fingers 33 resiliently urged vertically to the plane of the wipers, which fingers press the wipers against the underside of the shoe. The wipers, by swinging together in shears-fashion, fold the edge of the vamp 24 over the edge of the last 23. Longitudinally flexible tongues 10 and 11, which are recessed in the upper surface of each upper wiper element 12, 13 and are fixed thereon, for example, by means of rivets 14, near the toe portion of the wipers, are raised by means of a pressure element, for example, a pressure ram or post. These tongues are recessed surface-flush in grooves 19, 20, Fig. 3, and follow the edge contours of the inner edges of the wipers at a slight constant distance therefrom, as shown in Fig. 2. The tongues 10, 11 terminate at the waist of the last and include laterally projecting platforms 17, 18 which are engaged on their underside by pressure plates 21, 21' shown in Figs. 1, 4 and 5, against which pressure posts 26 bear, regardless of the position of the tongues 10, 11, i.e. the angular displacement of the wipers.

As shown in Fig. 1, the tongues 10, 11 preferably have extensions 15, 16 following the contours of the inner sole 25 beyond the platforms 17, 18 and extending to the waist. Due to vertical force imposed the pressure posts 26 which are moved by a pressure element 30 engaging a two-armed lever 29 midway its length to compensate for height variations and to equalize pressure, the tongues 10, 11 are pressed against the curvature of the last progressively from the toe portion of the shoe, over the ball up to the waist so that the edge of the vamp resting on the tongues will be uniformly applied and caused to adhere firmly without the use of any additional fasteners such as tacks.

The tongues 10, 11 are preferably made from spring steel. However, the tongue may be made of highly flexible material. In this case pressure posts 26², as can be seen from Fig. 5, are connected with flexible tongues 15² by means of a ball joint 31 to make retraction possible.

Moreover, tongues 15¹ (Fig. 6) may be used which consist of spaced plates arranged one following the other in a row and on the underside of each of these plates 45 being engaged by a hinged pressure post 26¹ so that the tongues can readily conform to different curvatures.

The invention is not restricted solely to the form of construction illustrated, but the shape and arrangement can be varied within the scope of the invention according to actual conditions and the characteristics of the lasting machine in which it is incorporated.

I claim:

1. A lasting machine comprising a wiper arrangement for lasting an upper on a last which is retained with the sole substantially horizontal and the waist portion curved upwardly therefrom, a pair of substantially planar wiper elements movable horizontally beneath the sole for wiping the toe portion of the shoe upper over the edge of the sole thereof, an element including resilient means engageable with the wiper elements in their horizontal movement for urging the same into pressing relation toward the sole, said wiping elements including longitudinally flexible pressing tongues recessed in the upper surface thereof and fixed adjacent one end for disposition beneath the toe portion of the sole, said tongues being engageable at the edge of the sole from the toe portion to the waist and being progressively displaceable vertically from said toe portion of the wiper elements and terminating in free ends, pressure portions on said tongues adjacent said free ends, and vertically displaceable force transmitting means engageable at said pres-

sure portions for applying pressure adjacent the ends of said flexible tongues and forcing the edge of said upper from the toe portion to the waist into contact with said last.

2. The structure of claim 1; said vertical force transmitting means including means for equalizing pressure on said pressure portions.

3. The structure of claim 1; said flexible tongues comprising a series of plate members each hingedly connected to an individual force applying element.
